UNITED STATES PATENT OFFICE

JOSEPH A. KEHRER, OF COLUMBUS, OHIO

FOLDING TABLE

Application filed March 5, 1929. Serial No. 344,848.

This invention relates to folding tables and has for one of its objects to provide a table of this character with novel means for maintaining and locking the legs thereof in a vertical position when extended and for holding the legs in collapsed position or in parallelism with respect to the surface of the table when the table is stored away or when not in active use.

10 Another object of the invention resides in the provision of a table which is simple in its construction, strong, durable, compact when folded, conveniently set up when desired and comparatively inexpensive to manufacture.

15 With these and other objects in view the invention consists in the novel construction, combination of elements and arrangement of parts hereinafter to be fully described and pointed out in the appended claims.

20 In the accompanying drawings:

Figure 1 is a perspective view of a table formed in accordance with the present invention,

25 Figure 2 is a perspective view showing the under side of one end of the table and the mechanism for holding the legs in an extended position,

Figure 3 is a similar view showing the legs in a folded position,

30 Figure 4 is a detailed vertical sectional view taken on the line 4—4 of Figure 2.

Referring more particularly to the drawings, the numeral 1 designates the top of the table, which is preferably of a rectangular form or contour. Mounted on the under surface of the top 1 is a pair of spaced longitudinally extending bars or brace members 2 and 3 which extend substantially the full length of the table top 1 and are positioned near the longitudinal edges thereof.

35 Pivottally connected as at 4 and 5 to the outer ends of the bars 2 and 3 are leg members 6 and 7, which are connected in pairs by means of strips 8 secured to the opposite ends of the legs 6 and 7. The strips are also positioned on the leg members so that one of their edges are flush with the upper end edges of the legs and abut against the under side of the table top 1 when the legs are in an extended position. Thus, the strips 8 together with the

bars 2 and 3 form a rectangular frame which serves to brace the top 1 both longitudinally and vertically thereof and at the same time give the table a finished appearance.

Arranged between and pivotally connected, 55

as at 9, to an intermediate portion of the leg members 6 and 7 are triangularly formed links 10 which extend in opposite directions with respect to each other. Each of these links include a pair of upwardly and angularly directed braces 11 and 12 which are united near their outer ends by a transversely extending connecting bar 13. The inner ends of the braces 11 and 12 are pivotally connected to a sliding bar 14 arranged in the longitudinal center of the table top 1 and are positioned on the under side thereof. The bars 14 are guided for sliding movement within a pair of spaced brackets 15 and 16 which are secured by means of screws or other fastening 60

elements 17 to the under side of the table.

The spring 18 is secured to the bracket 16 and positioned between the bar 14 and the top 1

serving to force the bar in a downward direction so as to frictionally engage with the 70

lower part of the brackets thus holding the leg members securely in their folded position.

To lock the leg members of the table in their extended position and to prevent accidental 75

collapse thereof each of the bars 14 are provided with a notch 20 in the lower edge thereof which is of a width substantially equal to that of the lower bar of the bracket 16.

The notches 20 are adapted to register with and to receive the brackets 16 due to the action of the springs 18 when the legs are in their extended position, as will be readily understood by referring to Figures 2 and 3 of the drawings.

When it is desired to fold the legs the bars 14 are pressed against the action of the 80

springs 18 so as to disengage the notches from the brackets 16 permitting the bars to be shifted inwardly upon the swinging of the legs, as

will be obvious.

From the foregoing description taken in 85

conjunction with the drawing, it will be seen that a folding table of simple and durable construction is provided and that the same may be easily and quickly manipulated to support the table in an elevated position or to permit 90

100

the same to be collapsed when not needed in active use. The many advantages of the folding table can be readily understood and although I have illustrated the preferred form and arrangement of the various parts, it will be understood that the invention is susceptible of considerable modification without departing from the essential features or sacrificing any of the advantages thereof which will fall fairly within the scope of the invention as claimed.

What is claimed is:

1. A folding table comprising a top, two pairs of end legs pivoted to said top, two sets of brackets arranged centrally and longitudinally of the table, a bar slidably mounted in each set of said brackets, triangularly formed links connecting said bars and said legs, said bars being formed with notches in their lower edges adapted to receive certain of said brackets, and spring members engaging with the bars and serving to maintain the sliding bars in any one of their set positions.
2. A folding table comprising a top, two pairs of end legs pivoted to said top, two sets of brackets arranged centrally and longitudinally of the table, a bar slidably mounted in each set of said brackets, angularly formed links connecting said bars and said legs, said bars being formed with notches in their lower edges adapted to receive certain of said brackets, and spring members engaging the bars and serving to maintain the notches of said bars in engagement with said brackets when the leg members are in their extended positions.

In testimony whereof I affix my signature.
JOSEPH A. KEHRER.
